UNITED STATES PATENT OFFICE

CHARLES FRANCIS JENKINS, OF WASHINGTON, DISTRICT OF COLUMBIA, ASSIGNOR
TO C. FRANCIS JENKINS, INC., OF WASHINGTON, DISTRICT OF COLUMBIA

AIRPLANE RADIO EQUIPMENT

Application filed August 23, 1929. Serial No. 387,894.

This invention relates to radio equipment carried aboard an airplane, and has for its principal object a simple assembly of parts which wholly avoids interference from the electrical equipment of the engine.

Heretofore it has been customary in airplane-radio equipment (a) to suspend a wire under the plane with a lead weight, "a lead fish" attached to the free end thereof to hold it steady, and as nearly vertical as possible; or (b) to fasten the antenna to a vertical mast carried by the plane. (c) Antennae have also occasionally been fastened along the leading edge of the wings, and (d) from wing tip to tail structure.

All such antenna locations have serious interference from engine ignition system radiation. For this reason costly shielding of the magnetos, the spark plugs and high-tension leads must be employed to avoid ignition noises in the exposed antenna preventing voice reception aboard the plane, and seriously interfering with code reception.

Electrical high-tension radiation from the engine ignition system is spherically radiated, and envelops the plane, but by exploration it has been discovered that there exists a radiation-free zone aft of the plane. This probably results from absorption by the metal parts of the plane fuselage, creating an electrical shadow, and an interference-free zone behind the plane.

Whether this theory is correct or not, it has been found that there is an interference-free zone aft in the line of flight; and that if the antenna is held axially in this zone, no interference to radio signal reception results.

In putting this discovery into useful service a shielded radio set is mounted in the plane, in any convenient place. The ground wire is fastened to the metal work of the plane, acting as a counterpoise. The antenna lead-in end is run through a shield, the unshielded end of the antenna flying aft from the tail structure. The free end of the antenna or antenna wire has a very light weight drag attached thereto to keep it taut.

This drag may be for example, a small celluloid ball, although preferably a body of

stream-line form. A balsam-wood "fish" serves quite satisfactorily. A "fish" with screw-pitched fins thereon also assists in preventing it flopping in the slip stream by causing the "fish" to rotate rapidly in the extended axis of the wire. Of course a swivel is employed between the wire and the "fish".

In the drawing herewith illustrating the invention, A is an airplane, in which is a radio set B, with an antenna C, attached thereto. On the free end of the antenna a light weight drag E is fastened. The lead-in end of the antenna is shielded in a tube D.

The operation of the invention is so obvious to those skilled in the airplane-radio art as to need scarcely more than a brief description.

Whether the antenna is thrown overboard after the plane is in flight, as was done in applicant's first experiments, or is unreeled from a spool until the right length of antenna is flying, is immaterial; in either event the drag holds the wire taut in the electric shadow in the wake of the plane, which is the object sought, namely, that the antenna does not pick up any radiation from the ignition system of the engine.

Incidentally the antenna with a light weight drag holding it axially in the slip-stream creates far less parasitic resistance than either a depending antenna or a mast supported antenna.

Also this location of the antenna permits the use of such a length of wire as will tune to the primary of the broadcast frequency, which is a more efficient method than the employment of a short antenna tuned to a harmonic frequency.

Quite obviously it is easier, and far less expensive to shield the radio set than it is to shield the engine ignition system; which latter also gives unending trouble in engine servicing and repair.

What I claim is—

1. The combination with an airplane having a metallic structure including an engine and consequent engine system radiation, by reason of which metallic structure an interference free zone is created, of a radio set mounted on the airplane in the rear of the

engine, and an antenna connected to the radio set and projecting from the airplane through the tail thereof to fly in substantially a horizontal plane and axially of the plane behind the airplane and its engine within the interference free zone whereby there is prevented interference from engine ignition radiation without shielding the magnetos, spark plugs and high tension leads.

10 2. The combination with an airplane having a metallic structure including an engine and consequent engine system radiation, by reason of which metallic structure there is created an interference free zone extending 15 behind the airplane, of a shielded radio set mounted within the airplane in the rear of the engine, an antenna connected to the radio set and projecting from the airplane through the tail thereof to fly in substantially a horizontal plane and substantially axially of the airplane and behind the airplane and its engine in the interference free zone whereby there is avoided interference from engine ignition radiation, and means carried at the 20 outer end of the antenna to maintain the same taut in said radiation-free zone aft of the airplane.

3. The combination with an airplane having a metallic structure including an engine 30 and consequent engine system radiation, of a shielded radio set mounted within the airplane in the rear of the engine, a tube in the airplane leading rearwardly from the shielded radio set to and through the tail of the airplane, and an antenna connected to the radio set and passing through said tube and shielded thereby within the airplane and having its outer portion projecting therefrom to fly unshielded in substantially a horizontal 35 plane and substantially axially of the airplane behind the latter and its engine and within an interference free zone created by parts of the metallic structure whereby there is avoided interference from engine ignition 40 radiation.

4. The combination with an airplane having a metallic structure including an engine and a consequent engine system radiation, of a radio set mounted within the airplane in 50 the rear of the engine, and an antenna connected to the radio set and projecting from the airplane so as to fly in substantially a horizontal plane behind the engine and within an interference free zone created by the metallic structure whereby there is avoided interference from engine ignition radiation without shielding the magnetos, spark plugs and high tension leads.

5. The combination with an airplane having a metallic structure including an engine and consequent engine system radiation, of a radio set mounted on the airplane in the rear of the engine, an antenna extending from the radio set to and beyond the tail of the airplane and unconnected with the tail, the por-

tion of the antenna beyond the tail being the only portion thereof exposed outside the airplane and being maintained taut in a substantially horizontal plane substantially axially of the airplane behind the tail of the airplane incident to forward movement of the airplane in flight and being located within an interference free zone created because of electrical shadows cast by the metallic structure and thereby rendered free of interfering disturbances incident to engine system radiation.

6. The combination with an airplane having a metallic structure including an engine and a consequent engine system radiation, part of said metallic structure creating an electrical shadow and a resulting interference free zone, of a radio set mounted within the airplane in the rear of the engine, an antenna located behind the engine and wholly within said zone and connected to the radio set and having its outer end projecting from the rear of the airplane to fly in substantially a horizontal plane and substantially axially of the airplane and its engine whereby there is avoided interference from the engine ignition system, and means carried at the outer end of the antenna to maintain the same taut in said substantially horizontal plane.

7. The combination with an airplane having a metallic structure including an engine and a consequent engine system radiation, of a radio set mounted within the airplane in the rear of the engine, and an antenna connected to the radio set and having its outer end projecting from the rear of the airplane to fly in substantially a horizontal plane and substantially axially of the airplane and its engine to prevent interference from the engine ignition system.

8. The combination with an airplane having a metallic structure including an engine and a consequent engine system radiation, of a radio set mounted within the airplane in the rear of metallic structure that creates an electrical shadow in the rear of the engine, an antenna connected to the radio set and having its outer end projecting from the airplane only at the rear thereof to fly only in the rear of the airplane and in a substantially horizontal plane during the flight of the airplane so as to confine the disposition of the trailing antenna in the radiation-free zone aft of the airplane and created by said electrical shadow.

9. The combination with an airplane having a metallic structure including an engine and a consequent engine system radiation, which metallic structure casts an electrical shadow aft that part of the engine system that produces said engine system radiation, of a radio set mounted within the airplane in the rear of the engine, and an antenna which is located wholly within said electrical shadow, which is connected to the radio set,

and which has its outer end always disposed in substantially a horizontal plane during the normal forward flight of the airplane whereby the antenna during the normal forward flight remains in the radiation-free zone created by said electrical shadow.

10. In radio equipment aboard a tractor engine airplane having an interference free zone aft the engine, an antenna located aft 10 the engine and wholly within the interference free zone and approximately parallel to the axis of the fuselage of the plane.

In testimony whereof I have affixed my signature.
